UNITED STATES PATENT OFFICE

2,011,234

CARPET WASHER

Joseph S. Thompson, San Francisco, Calif.

Application July 17, 1933, Serial No. 680,767

7 Claims. (Cl. 15—50)

The invention in general relates to cleaning devices, and more particularly relates to means for removing stains from carpets, floors and like surfaces.

5 The embodiment of my invention which is illustrated and described herein is an improvement of the spot cleaning device of my invention which is disclosed and claimed in Letters Patent of the United States, No. 1,892,792, issued to me on January 3, 1933.

It is an object of the invention to provide a self-propelled carpet or surface washing device which affords continuous circulation of a cleaning fluid about the area traversed by the device in operation.

15 Another object of the invention is to provide a device of the aforementioned character which affords automatic reversal in the direction of flow of the circulating cleaning fluid over a soiled 20 surface upon a reversal in direction of movement of the device.

A still further object of the invention is to provide a device of the character specified which compensates for uneven surfaces encountered 25 and hence avoids misapplication of the cleaning fluid.

Another object of the invention is to provide a carpet-washing device which affords circulating application of a hot cleaning fluid to the 30 soiled or spotted carpet without damaging the fabric.

The foregoing and other objects of the invention are attained with the embodiment of the invention which is illustrated in the accompanying drawings, in which:

Figure 1 is a side elevation, partly in cross-section, of an embodiment of the invention.

Figure 2 is an enlarged, sectional elevation of certain connected details of the embodiment of 40 the invention shown in Figure 1.

Figure 3 is an elevation, partly in cross-section, of other certain details of the embodiment of the invention.

Figure 4 is a view taken on the section line 45 4—4 of Figure 1.

Figure 5 is an enlarged cross-sectional elevation of one portion of the embodiment of the invention which is illustrated in Figure 1.

Figure 6 is a view of the detail shown in Figure 3 and taken on the line 6—6 thereof.

Figure 7 is an enlarged sectional elevation of a modified embodiment of the connected parts which are illustrated in Figure 2.

Figure 8 is a sectional elevation of a portion of 55 a modified embodiment of the invention.

Figure 9 is a sectional elevation of another form of that portion of the modified embodiment of the invention which is illustrated in Figure 8.

Figure 10 is a plan of a modification of one portion of the embodiment of my invention.

Figure 11 is a cross-sectional view of the modification of my invention taken on the line 11—11 of Figure 10.

In its preferred form, the carpet or surface washing device of my invention preferably comprises a carriage, means for propelling the carriage, a tank for holding a cleaning fluid supported on the carriage, together with a washing head supported adjacent the carpet or surface to be cleaned, means for circulating the cleaning fluid about the washing head in the direction counter to the direction of movement of the carriage, and means for automatically reversing the direction of flow of the fluid across the carpet or surface upon a reversal in the direction of movement of the carriage.

As illustrated in Figure 1 of the drawings, I provide a carriage which includes a framework 11 supported upon a pair of rollers or wheels 12, the wheels being mounted upon an axle 13 which is journaled in bearings 14 carried by the framework. A handle or guide-bar 16, secured to the framework, is provided for moving the machine about when not in operation.

In the embodiment of the invention illustrated, there is included a tank 17 which is removably mounted upon the framework 11, a prime mover, such as a motor 18, for propelling the carriage, a washing head 19, and means for circulating a cleaning fluid from the tank about the washing head and over soiled spots or areas on the carpet or other surface being washed, said means including a gear, vane, or other type of pump 21 which is driven by the motor, a conduit 22 which establishes communication between the tank 17, through a valve head 23, and the washing head 19, together with a return pipe 24 leading from the pump 21 to the top of the tank 17.

The tank 17 for holding the cleaning fluid may be fabricated of any relatively light metal or other suitable material and preferably is supported by the framework intermediate the guide-bar 16 and the motor and pump assembly. Preferably, the tank 17 is automatically self-sealing upon removal thereof from the carriage, and automatically establishes communication with the conduit 22 upon installing the tank in position upon the framework. With particular reference to Figures 1 and 2 of the drawings, it will be observed that the bottom of the tank is recessed and

a tube 26 is secured in the recess. The tube may take any desired form, although in the present embodiment a cylindrical tube having a valve seat 27 formed upon its inner end is employed. 5 A web 28, having a central bore 29, is formed in the tube for slidably supporting the shank of a poppet or other type of valve 31. Co-operating with the tube 26 is a sleeve 32 which is in threaded engagement with a boss 33 formed upon the valve head 23 of the conduit 22. If desired, the tube 26 can be provided with a flared portion or apron 34 at its outer end, which will serve as a guide for the sleeve 32 when the tank is placed upon the carriage. The sleeve 32 carries a pin 36 which 10 engages the shank of the valve 31 to lift the same from its seat 27 when the tank is in position on the framework 11. Upon removing the tank from the carriage for replenishing the cleaning fluid or substituting a fresh supply thereof, the valve 15 31 drops upon its seat 27 and effectively seals the tank.

For propelling the carriage, I preferably employ an electric motor having an extended shaft 37 which, through suitable gearing, drives an auxiliary shaft 38 journaled in bearings 39 which are mounted upon the framework of the carriage. The arrangement is such that the auxiliary shaft 38 may be driven in either a clockwise or a counter-clockwise direction, at the will of the operator 20 of the device, so that the carriage may be propelled in a forward or a backward direction. The driven shaft 38 is placed in driving connection with the axle 13 preferably by means of sprockets and a chain drive 41.

Preferably, a reversible bevel gear connection is employed between the motor shaft 37 and the auxiliary shaft 38 for effecting movement of the carriage in a forward and in a reverse direction. The reversible bevel gear drive connection preferably includes a stub shaft 42 which is journaled in bearings 43 carried in a housing 44 supported on the framework. The stub shaft 42 is given unidirectional movement by means of a worm 46 carried on the extended motor shaft 37 which meshes with a worm wheel 47 mounted on the stub shaft. The stub shaft 42 carries an axially movable sleeve 48 upon which is carried a pair of bevel gears 49 and 51, either one of which, depending upon the desired direction of movement of the carriage, is placed in engagement with a bevel gear 52 mounted upon an auxiliary stub shaft 53 which is journaled in a bearing 54 carried by the housing 44. The auxiliary stub shaft 53 also carries a bevel gear 56 which is in constant engagement with a bevel gear 57 carried by the auxiliary shaft 38. In order to move the sleeve 48 axially in either direction along the shaft 42 and hence to place either the gear 49 or the gear 51 into engagement with the bevel gear 52, I provide a lever 58 which may be positioned upon the guide bar 16 of the device and which controls through suitable linkage 58a (Fig. 6) a pin 59 which is disposed in a groove 61 formed in the sleeve 48. A pull upon the lever 58 causes the pin 59 to move the sleeve in one direction to place one of the gears 49 or 51 into engagement with the gear 52, and, contra, a push upon the lever 58 will effect the movement of the sleeve 48 in the opposite direction.

In accordance with the invention, the washing head 19 preferably comprises a shell 62 in which is formed a chamber 63 having an inlet 64 and an outlet 66, the outlet communicating with channels 67 and 68 which are formed in the shell below the chamber 63 and which terminate at the base

of the shell. An additional channel 69 is formed in the shell 62, the termini of which are at the base of the head. Preferably, the washing head is supported upon the device by means of a swivel mounting in order that the head may conform to uneven or undulatory surfaces over which the carriage may ride. For supporting the head, I conveniently provide a pipe 71 which is connected to the pump 21 and which establishes communication between the pump and the channel 69 of the head. The swivel mounting includes a relatively short pipe connection or sleeve 72 which is movably fastened in the pipe 71 and which extends therefrom, the head 19 and the sleeve 72 moving about the pipe 71 when undulatory surfaces are encountered. The extended sleeve 72 is threaded to receive a threaded extension 73 of the shell 62, as shown in Figure 5 of the drawings. The mounting for the washing head 19 also includes a pipe 74 which is threaded into a cap 76 and which carries a threaded extremity 77 for receiving the threaded portion of the inlet 64 of the shell. The pipe 74 is provided with ports 78 which are held in registry with the conduit 22 and hence establish communication between the conduit 22 and the chamber 63 of the washing head.

The washing head 19 also includes an interior web 79 for supporting a heating element 81 within the chamber 63 so that the washing fluid may be heated as it passes through the washing head and prior to being disposed or deposited upon the carpet or surface being cleaned. The heating element preferably is electrical and derives its power from the same source as the motor 18.

As illustrated in Figures 4 and 5 of the drawings, a plate 82 is slidably supported on the base of the shell 62 and is moved between two extreme positions by surface friction between it and the surface being cleaned. Any suitable means for mounting the plate can be employed, although, as illustrated, I have provided bolts 83 which are secured to the plate 82 and which slide in grooves 84 formed in the base of the shell. The plate 82 is provided with channels 86 and 87 and also is recessed to provide, in conjunction with the carpet or other surface being cleaned, a chamber 88 for the washing fluid. In Figure 5 of the drawings I have illustrated the position that plate 82 assumes when the carriage is propelled in a forward direction. In this position it will be observed that the channel 87 of the plate is in registry with the channel 68 of the shell, and, further, that the channel 86 of the plate 82 is in registry with the channel 69 of the shell. Upon a reversal of movement of the carriage the plate 82 assumes a position at the forward end of the shell 62 so that channel 86 of the plate is in registry with channel 67 of the shell and channel 87 of the plate is in registry with channel 69 of the shell. The changes in position of the plate 82 upon a change in direction of movement of the carriage afford a change in direction of flow of the washing fluid, so that the fluid will always flow counter to the direction of movement of the device. The arrows of Figure 5 indicate the direction of flow of the fluid through the washing head.

Inasmuch as the washing head 19 is supported adjacent the floor or other surface being cleaned and is positioned below the tank 17 on the framework, the fluid will flow from the tank 17 to the washing head by gravity and by force of its head. An adjustable needle valve 89 is provided and sup-

ported in the valve head 23 of the conduit 22 for controlling the flow of cleaning fluid to the washing head.

In Figure 7 of the drawings I have shown a modified form of valve for controlling the flow of fluid from the tank 17 to the conduit 22. In this modification the needle valve 89 is dispensed with, the transverse pin 36 carried by the sleeve 32 is also eliminated, and a relatively long pin 91 is provided which extends longitudinally of the sleeve and is slidably mounted in an interior web 92 on the sleeve 32 as well as in a boss 93 formed on the head 23 of the conduit 22. Preferably, the head 23 and the sleeve 32 are formed integral. To actuate the pin 91 I provide a finger 94 which is pivotally connected to a bracket 96 carried by the valve assembly and which engages the exposed or lower end of the pin. Movement of free end 97 of this finger will effect a raising or a lowering of the pin 91 to unseat and permit seating of the valve 31.

To operate the device it is necessary only to connect the motor and heating element circuit to a source of current and to close the switch in the circuit to start the motor and the pump and to energize the heating element. The valve 89 is then opened to permit flow of the washing fluid from the tank 17 to the washing head. With the carriage moving in a forward direction, the plate 82 upon the washing head assumes a position as shown in Figure 5 of the drawings, and the pump 21 will draw the cleaning fluid upon its suction stroke through the washing head, through the channel 68 of the shell and the channel 81 of the plate, across the soiled area confined by the chamber 88, and back through the channel 69 of the washing head into the pipe 71 leading to the pump 21. The outlet of the pump communicates with the return pipe 24 from whence the fluid is conducted back to the tank 17. Upon a reversal in direction of movement of the carriage, the plate 82 of the washing head slides to the forward part of the shell and the fluid is drawn through the washing head, through the channel 67 of the shell, through the channel 86 of the plate, across the soiled surface up through the channel 87 of the plate to the channel 69 of the shell, and thence through the pipe 71 and the pump 21 back to the tank 17. The shifting of the plate 82 automatically, it will be observed, changes the direction of flow of the cleaning fluid over the soiled area, so that it will always flow counter to the direction of flow of the movement of the carriage. To discontinue operations, the valve 89 is first closed and the motor and the pump operated for a short period to flush the cleaning fluid from the device and carry the fluid back to the tank 17. When the washing fluid in the tank 17 becomes unfit for further use, the tank can be removed from the framework 11, the valve 31 immediately and automatically seating upon its seat 27 to seal the tank and hence prevent any discharge of the fluid from the tank 17.

Although I have illustrated the device of my invention as including a tank 17 for holding a cleaning fluid which is supplied to the washing head 19 and drawn over the surface being cleaned by means of a pump, the tank 17 may be dispensed with, if desired, and the hose 22 may be connected directly to a hot water tap; the return pipe or hose 24 from the pump exhaust being led to a suitable drain. With this type of arrangement, means can be provided for introducing soap or other cleanser into the hot water flowing through hose 22, such as, for example, a liquid

soap container which can be connected into the hose 22 in any suitable and conventional manner. In Figures 8 and 9 of the drawings I have illustrated two embodiments of soap feeding means. With particular reference to Figure 8, I provide a casing 101 divided into two compartments 102 and 103, the compartment 102 being air-tight and serving to hold a quantity of liquid soap. The compartment 103 or turbulence chamber has an inlet 104 provided with a nipple 106 to which a hose 107 leading from a hot water tap is connected for communication with the chamber 103. An outlet 108 is formed in the compartment 103 and likewise is provided with a nipple 109 to which the conduit 122, leading through a valve as in Figure 7 to the washing head of the device illustrated in Figures 1 to 4 inclusive, is connected. The turbulence chamber is provided with baffles 111 and 112 to assist the mixing of the liquid soap and the hot water. The liquid soap is introduced into the compartment 103 by means of a passage 113 which is controlled by any suitable valve, such as the needle valve 114. The soap feeding device illustrated in Figure 8 of the drawings also includes means, such as a pipe or conduit 116, for equalizing the pressures in compartments 102 and 103.

In Figure 9 of the drawings I have illustrated a modified form of soap feeding means in which the pressure equalizing means of the device is substituted by an air and water compartment controlled by a suitable valve. This modification comprises a casing 201 divided into three compartments or chambers, including a liquid soap chamber 202, a turbulence or mixing chamber 203 and an air and water compartment 205 of greater dimensions than the liquid soap chamber 202. As in the modification of Figure 8, the mixing chamber 203 has an inlet 204 provided with a nipple 206 to which a hose 207 leading from a hot water tap is connected for communication with the chamber 203. An outlet 208 is formed in the compartment 203 and is provided with a nipple 209 for receiving the conduit 222 which leads through a valve as in Figure 7 to the washing head of the device of my invention. The chamber 203 is provided with baffles 211 and 212 to assist in mixing the soap and hot water which is fed to the washing head. In this modification of soap feeding device, a passage 213 connects the compartments 202 and 203 and a needle valve 214 controls the flow of liquid to the chamber 203. An indicator 215 is provided for observing the level of the liquid soap. The chambers 202 and 205 are air-tight and a partition 216 divides them. Mounted within the compartment 205 is a valve 217 for controlling an inlet 218 at the base of the compartment 205, the valve being carried by a valve stem 219 which is adapted to be placed in threaded engagement with a sleeve 220 which is carried by a wing nut 221 and which pierces the top or cover 223 of the compartments 202 and 205. Screwing the sleeve 220 upon the valve stem 219, when placing the cover on the casing 201, raises the valve 217 against the action of a spring 224 to permit flow of water into compartment 205. Upon removing the cover of the compartments 202 and 205, the wing nut 221 is rotated in the opposite direction and the sleeve 220 releases the valve stem 219 thereby permitting the seating of the valve 217 by force of the action of the spring 224. The compartment 205 is provided with an outlet 225 controlled by a check valve 226 which opens when the cover of the compartment is removed by the pressure of the water 75

therein, to permit draining thereof through the outlet 225.

In the carpet washer of my invention, I preferably provide means for shifting or nudging the front of the washing head to the right and to the left in order substantially to maintain a given course of travel of the device. As illustrated in Figures 10 and 11 of the drawings, I mount a pair of nudging devices, designated generally by the reference numeral 311, upon the trailing edge or back of the washing head 319. One device 311 is mounted at one end of the back of the head and faced inwardly, while the other device 311 is mounted at the opposite end of the back of the head and also faced inwardly, so that the two nudging devices face towards each other. Each nudging device preferably comprises a lever 321 which is journaled in the housing of the head 319 and which is pivotally connected, by means of a bell crank 322, to a platform or shoe 323. The shoe 323 is pivotally mounted to the bell crank and is normally carried clear of the surface being washed by means of an arm 324 of the bell crank, which carries a lip 326 extending over and resting upon the lever 321, as well as by means of a spring 327 which urges the lever 321 against a stop 328 secured to the washing head.

In order to shift or nudge the head 319 to the left, or in a direction as indicated by the arrow 329 in Figure 11 of the drawings, it is only necessary for the operator to depress the pedal 331 of the device 312 at the opposite end of the head.

As illustrated in Figure 10 of the drawings, the head 319 conveniently is provided with means for guiding the head when working along walls. These means preferably comprise a pair of wheels or rollers 333 and 334 which are journaled in the head housing at opposite sides of the front of the head. As shown, the mounting of the wheels is such that each protrudes slightly from the side of the head for engaging the wall adjacent which the machine may be working, thus guiding the head. Preferably, the wheels are covered with a resilient substance such as rubber, to protect the wall from abrasion. In this connection it is to be noted that the wheels 333 and 334 are mounted so as to extend forwardly of the head so that upon approaching and engaging a wall with the device, the wall is protected from damage.

While I have illustrated the preferred embodiment of my invention in the accompanying drawings, it is to be understood that I am not to be limited to the embodiment shown, as my invention, as defined in the appended claims, can be embodied in a plurality and variety of forms.

I claim:

1. In a surface-washing device, a washing head adapted to be moved back and forth over the surface to be washed, a plate slidably supported on said head and adapted to rest upon said surface, said plate having a recess therein which forms, in conjunction with the surface to be washed, a chamber for the passage of washing fluid, and means controlled by sliding movements of the plate relative to the head for reversing the direction of flow of washing fluid through said recess.

2. In a surface-washing device, a washing head adapted to be moved back and forth over a surface to be washed, a plate slidably supported upon said head and adapted to rest upon said surface, said plate having a recess therein which forms, in conjunction with the surface to be washed, a chamber for the passage of a washing fluid, means for supplying a washing fluid to said chamber,

and means controlled by the positioning of the plate relative to the head for drawing the fluid across said chamber counter to the direction of movement of the device and for withdrawing the fluid from said chamber irrespective of the direction of movement of the device.

3. In a surface-washing device, a washing head adapted to be moved back and forth over the surface to be washed, two sets of spaced passages in said head, one set serving to deliver washing fluid to an area of the surface operated upon and the other set serving to remove the fluid from said contact, and means for changing the direction of flow of washing fluid across said area in accordance with a change in the direction of movement of the head, said last means including a member carried by the head for limited movement relative thereto, said member having one surface thereof adapted to frictionally contact said surface, said member also being provided with a fluid recess and spaced fluid inlet and outlet ports selectively communicating between the recess and the two sets of passages in the head.

4. In a surface-washing device, a washing head adapted to be moved back and forth over the surface to be washed, two sets of spaced passages in said head, one set serving to deliver washing fluid to an area of the surface operated upon and the other set serving to remove the fluid after such contact, and means for changing the direction of flow of washing fluid across said area in accordance with a change in the direction of movement of the head, said last means including a plate slidably carried by the head for limited movement relative thereto, said plate having one face thereof adapted to frictionally contact said surface, said plate being also provided with a fluid recess interrupting said plate, together with spaced fluid inlet and outlet ports selectively establishing communication between the recess and the two sets of passages in the head.

5. In a surface-washing device, a member having a substantially flat face interrupted by a recess, whereby when said face is contacted with a surface to be treated a confined chamber is defined by the recess and said surface, means including a head for causing flow of washing or cleaning liquid through the chamber thus formed, the member having spaced ports for the flow of liquid into and from said chamber, and means for reversing the direction of flow through said ports and said chamber in response to a change in the direction of movement of the device, said last means including a connection between said member and said head affording limited relative movement between the same.

6. In a surface-washing device, a washing head adapted to be moved back and forth over the surface to be washed, a member underlying the head and carried by the same for limited relative sliding movement, the lower face of the member being adapted to frictionally engage said surface, whereby the member assumes either one of two limiting positions in accordance with the direction of movement of the head, a recess formed in the lower face of the member, separate fluid passages in the head for delivering and removing washing fluid, and means for establishing communication between said recess and said passages for flow of fluid in opposite directions through said recess for said two limiting positions of the plate relative to the head.

7. In a surface-washing device, a member having a substantially flat face interrupted by a

recess, whereby when said face is contacted with a surface to be cleaned a confined chamber is defined by the recess and said surface, means for circulating a washing or cleaning liquid through the chamber thus formed, the member having spaced ports for the flow of liquid into and from

the chamber, and means for reversing the direction of flow through said ports and said chamber in response to a change in the direction of movement of the device over said surface.

5

JOSEPH S. THOMPSON.
